Inventor:

Thomas G. Estes

United States Patent Office.

THOMAS G. ESTES, OF FALL RIVER, MASSACHUSETTS.

Letters Patent No. 67,640, dated August 13, 1867.

IMPROVED MODE FOR STRIKING GONGS OR BELLS.

The Schedule referred to in these Letters Patent and making part of the same.

TO ALL WHOM IT MAY CONCERN:

Be it known that I, THOMAS G. ESTES, of Fall River, in the county of Bristol, in the State of Massachusetts, have invented a new and improved Mode of Striking a Gong, Bell, or Triangle; and I do hereby declare that the following is a full and exact description thereof, reference being had to the accompanying drawings, and to the letters of reference marked thereon.

My invention consists in the application of clock-work for striking a gong, bell, or triangle, as herein described.

Figure 1 is a perspective view of a gong and stand to which my invention is applied.

Figure 2 shows the machinery as seen from above, with gong and top plate of frame removed.

Figure 3 is a profile view with gong removed.

Figure 4 shows a portion of the stop-work of the machinery.

Fig. 1. A¹ is the gong; B¹ the stand; C¹ knob on the top of the main shaft.

Fig. 2. B² stand; D² main-spring; F² dog; G² arm attached to dog; H² hammer; a² a² a², etc., pins secured in and projecting above the upper surface of wheel L², (the latter is attached to main shaft P².) which pins strike successively against the arm I² of hammer as the wheel revolves, causing the hammer to strike the bell as many times as there are pins on the wheel.

Fig. 3. B³ stand; D³ main-spring; E³ lever; F³ dog; L³ wheel secured to shaft P³.

Fig. 4. E⁴ lever, shown by E² (fig. 2); K⁴ cam on lower end of the main shaft; c⁴ d⁴ pins to prevent the lever from moving too far in either direction.

Operation.

The different parts of my invention being constructed as shown and described, its operation may be noted. The cam on the lower end of the main shaft liberates the machinery when the main-spring is wound up, and bars it when run down. Turning knob C¹ (fig. 1) winds up the main-spring till at the end of one revolution the cam K⁴ (fig. 4) strikes against the outside of projection b⁴ (fig. 4) of lever E⁴, (fig. 4,) and carries back the lever till stopped by pin c⁴ (fig. 4.) As the lever moves back the free end strikes against projection x², (fig. 2,) which throws in the arm G² (fig. 2) clear of and frees the fly-wheel, permitting the shaft to revolve till it has made one revolution, when the cam K⁴ (fig. 4) strikes the inner side of projection b⁴ on lever E⁴, (fig. 4,) forcing the lever in till stopped by pin d⁴, (fig. 4.) The free end of lever pressing against point y² (fig. 2) throws the arm G² (fig. 2) out against the fly-wheel, preventing it from revolving till again liberated by winding up the main-spring. The number and time of strokes may be varied according to the desire of those using the bell.

I do not claim any mode previously invented or patented for striking gongs, bells, and triangles, but what I claim as my invention, and desire to secure by Letters Patent, is—

The combination of gong A¹, stand B¹, knob C¹, lever E³, dog F³, arm G², hammer H², and cam K⁴, with clock-work, as herein set forth and described.

THOMAS G. ESTES.
